COMBINATION DRESSING TABLE, STOOL AND STORAGE

Roxy Griffin, Canoga Park, Calif., assignor of one-tenth to Gadget-Of-The-Month Club, Inc., North Hollywood, Calif., a corporation of California.

Filed Mar. 23, 1959, Ser. No. 801,338

1 Claim. (Cl. 312—287)

This invention relates to furniture and more particularly to a combined dressing table, stool, and storage device.

It is an object of the present invention to provide an article of furniture that has several different uses, and which serves as an added convenience during various dressing and make-up operations.

It is another object of the present invention to provide an article of furniture of the above type which will store a large number of shoes in a convenient and accessible location at all times, and which can be used in all types of rooms.

Other objects of the invention are to provide a furniture unit bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

FIGURE 1 is an end elevational view, with parts broken away, of an article of furniture made in accordance with the present invention, with certain parts thereof in an open position;

FIGURE 2 is a top plan view of the unit shown in FIGURE 1, with parts broken away to show end-opening drawers forming a part thereof;

FIGURE 3 is a fragmentary side elevational view of the unit shown in FIGURE 1, with the side opening racks in a closed position.

Referring now more in detail to the drawing, a storage unit 10 made in accordance with the present invention is shown to include a substantially cubical housing 12 having depending feet 14 for supporting it upon a supporting surface. The top of the unit is provided with a substantially flat table top 16, while each side thereof is provided with a pair of vertically spaced apart and longitudinally extending rectangular openings 18, each of which is normally closed by a similarly shaped rectangular panel 20 that is pivotally secured to the housing by means of longitudinal hinges 22.

As is more clearly shown in FIGURES 1 and 2 of the drawing, each panel 20 is provided with a pair of pivotally connected folded braces 24 that are pivotally connected at their opposite ends by means of hinge pins 28 to the frame of the housing 12 and the respective closure panel 20, whereby rotation of the connected ends of the links 24 about their pivotal connection 26 will enable each such panel 20 to be moved to the closed position shown in FIGURE 3. Each panel 20 is also provided with a substantially perpendicularly related plate 30, which supports the toe portions of the shoes 36 placed within the rack. A brace 32 extends diagonally between the outermost end of the plate 30 and the upper end of each panel 20, at each longitudinal extremity of the panel, and a rod 34 extends longitudinally between the mid portions of each pair of braces 32. With the shoes 36 placed within the rack, the rod 34 engages the under surface of the shoe

2

in the joint between the heel and the arch, while the toe of the shoe rests upon the outer end of the plate 30. Thus, the racks may be opened and closed by rotating the members about the longitudinal hinges 22, without dislodging the shoes from supported engagement thereon.

Each end of the wall closure 12 is also provided with a substantially rectangular cutout 38 within which an elongated drawer 40 is slidably disposed. A pair of laterally spaced apart and longitudinally extending bars 44 serve as sliding support guides for each drawer 40, as shown in FIGURE 2. Dividers 46 separate the interior of each drawer 40 into individual compartments 48, each of which may be used to store stockings 50, or the like.

It will now be recognized that a small, compact, and attractive unit has been provided which can be conveniently used in any dressing room for keeping shoes, stockings, and other accessories in a convenient location at all times. Thus, any pair of shoes may be conveniently withdrawn simply by opening the respective racks, and choosing any one of the several pairs. The end opening drawers also serve as a convenient means for storing stockings, handkerchiefs, and the like, so that virtually all necessary items may be conveniently stored in a single unit.

While various changes may be made in the detail construction, it shall be understood that such changes shall be within the spirit and scope of the present invention as defined by the appended claim.

What I claim as new and desire to protect by Letters Patent of the United States is:

A storage unit comprising, in combination, a walled enclosure consisting of a substantially cubical unit having a substantially flat rectangular top and opposite sides, with each of said opposite sides having a pair of vertically spaced side opening rack means, each comprising a substantially rectangular opening, a panel hingedly supported at the bottom thereof upon said side of said enclosure for pivotal movement between an open and closed position relative to said rectangular opening, and a support for carrying a plurality of shoes within each said panel comprising a plate extending substantially perpendicularly inwardly from said panel at the bottom thereof, a brace extending diagonally between the innermost end of said plate and the uppermost end of said panel at each end of said panel, and a crossbar secured to the mid portion of each brace of each of said panels, said crossbar supporting said shoes intermediate the heel and the arch portion thereof, and the innermost end of said plate supporting the toe portion of each of said shoes, said perpendicular plate and said panel carrying same effectively closing the bottom portion of each of said rack means.
